Henry W. O'Dowd Inventor
By his Attorney J. H. Freeman

UNITED STATES PATENT OFFICE.

HENRY W. O'DOWD, OF PEEKSKILL, NEW YORK.

HEATING APPARATUS.

1,175,889.

Specification of Letters Patent.

Patented Mar. 14, 1916.

Application filed September 26, 1910. Serial No. 583,751.

To all whom it may concern:

Be it known that I, HENRY W. O'DOWD, a citizen of the United States, and a resident of Peekskill, Westchester county, State of New York, have invented certain new and useful Improvements in Heating Apparatus, of which the following is a specification.

My invention relates to heating apparatus; and, while it may be embodied in constructions adapted for various purposes, it is more particularly applicable to stoves used for making candy.

Objects of the invention are to provide an improved construction of the character referred to with which vessels of various sizes may be used; in which vessels of different sizes may be sustained at predetermined distances from the point of combustion; in which is regulated the passage through and from the combustion chamber of the heated products of combustion; in which the heat of the combustion chamber is conserved by the flue for the heated products of combustion, which shall be highly efficient and which shall be convenient and compact and simple and economical in construction and operation. These and other objects of the invention will in part be obvious and in part be made clear from the following description.

My invention consists in the novel parts, improvements, combinations and features of construction herein shown and described.

In the accompanying drawings, which are referred to herein and form a part hereof, is illustrated an embodiment of the invention, the same serving in connection with the description herein to explain the principles of the invention.

Of the drawings: Figure 1 is a sectional elevation of a candy stove constructed in accordance with my invention; Fig. 2 is a plan of the same taken on the line 2--2 of Fig. 1; and Fig. 3 is a sectional elevation of a detail.

A candy stove constructed in accordance with one feature of my invention includes in combination, a combustion chamber, a burner and a top for said chamber, said top comprising a series of sections arranged at different levels, each lower section being supported by the next upper section. According to one embodiment of this feature of my invention, said top sections comprise

a series of annular sections or rings, each ring having a vertically inclined portion, an upper flange portion adapted to engage a similar flange and be supported thereby, and a lower flange portion adapted to engage a similar flange.

According to another feature of the invention vents for the heated products of combustion are provided in the top side walls of the combustion chamber, and means for regulating the passage of the heated products of combustion through these vents are provided. The flue for the heated products of combustion is also arranged about the combustion chamber to serve as an additional source of heat. And oppositely flaring walls rise from the opposite sides of the burner to direct therefrom the flow of the heated gases.

Referring now in detail to the drawings, the embodiment of the invention illustrated, which is a candy stove, comprises a base 5 of suitable material, as shown, annular in shape and mounted upon suitable legs 6. Vertical annular lugs 7 and 8 extend from the base 5 and secure the superstructure of the stove, to which further allusion will be made. Preferably the inner edge of the annulus or base 5 is depressed to form an inwardly extending horizontal flange 9 upon which is secured as by bolts 11, a burner 12. This burner 12 is preferably and as shown, annular in shape and projects above the base 5, having in said projecting portion upwardly directed perforations or nozzles 13. The burner has an inlet 14 preferably made large enough to accommodate large size gas supply pipes, and also, using a reducer, the smaller sizes of supply pipe.

Rising from the base is a casing 15 preferably of cast iron lined with fire brick which forms the combustion chamber of the stove, preferably resembling in form an inverted frustum of a cone, having at its top a vertically extending portion 16 and at the base of said portion 16 an inwardly extending flange 17 which supports a regulating member hereafter to be described. Preferably also, fire bricks 19 and 20 are provided, the same, respectively, encircling and being encircled by the burner 12 and forming a recess into which the nozzles 13 bear. Preferably also, the sides 21, 22 of the respective fire bricks forming said recess are oppositely vertically inclined.

Suitable provision is made for the escape of the heated products of combustion. As shown, see Fig. 2, the vertical portion 16 forming the upper part of the casing 15 is perforated, preferably throughout its entire circumference, the vents 23 thus provided being of suitable dimensions and spaced apart and giving into a flue which will be presently described.

10 It will be seen that in a combustion chamber such as described, mixed currents at the bottom of the chamber will be avoided, and there will be a tendency to concentrate the heat in the space above the burner 12, where will rest the bottom of the vessel containing the material to be heated, to which further allusion will be made.

Another important feature of the invention resides in the provision of means for regulating the passage of the heated products of combustion through the vents 23 into the flue referred to. While this may be done in various ways, preferably and as shown, a regulating member 25 of dimensions similar to those of the vertical portion 16 is slidably mounted upon the flange 17 and is provided with perforations 26 similar to those of the portion 16 and adapted to register therewith. The regulating member 25 is also provided with a handle 28 which extends through slots 27, 27^a, and 27^b in the flange 16, casing 31, and the cover 33, respectively. These slots extend laterally and are of suitable extent to allow the handle 28 to be reciprocated so that the openings 23 and 26 of the portion 16 and member 25, respectively, may be brought into and out of register and thus regulate the passage of the heated products of combustion through the vents 23, as desired, see Figs. 1 and 2.

According to another feature of the invention, the escaping heated products of combustion are disposed of in such manner as to assist in conserving the heat in the combustion chamber. For this purpose, preferably and as shown, an outer casing 29 is provided extending entirely around the combustion chamber and coextensive in height therewith. It will be seen that the heated products of combustion passing through the flue thus formed before finally exhausting through a pipe 30 will maintain a high temperature in the space surrounding the combustion chamber and thus prevent any waste of heat energy within the latter. Preferably also, the said casing 29 is provided with a lining 31 of non-heat-conducting material, as asbestos, to prevent radiation of heat through the casing.

A top cover 33 is provided for the stove, the same, as shown, conforming in general outline to the wall 29 and overlapping the same. This cover is provided with downwardly depending annular lugs 34, 35, 36,

which serve to secure in position the top and members 15, 25, and 29, and the various parts of the stove are rigidly connected.

In order that vessels of different sizes for containing the candy or other material to be heated may be used, the usual reducing cover sections are provided, that is, cover sections which fit one within the other, as 37, 38, 39, 40 and 41. It will be noted, however, that as these cover sections are all on the same level, the smaller vessels would be farther removed from the place of combustion above the annular burner 12 where the vessels are of such shape as to project into the opening for which they are adapted. A prime feature of the invention, therefore, consists in the provision of means whereby vessels of the character referred to and of different sizes may be used, and yet the smaller vessels be disposed as near the place of combustion as the larger vessels. In the preferred embodiment of the invention illustrated, such means are provided as annular cover sections or drop rings which like the reducing cover sections 37 to 41 form a part of the top and comprise each a vertically inclined portion 42 and also upper and lower horizontal flanges, 43 and 44 respectively. But, by making the vertically inclined portion 42 of the drop ring of suitable extent the lower horizontal flange 44 will support the upper flange of the next lower ring so that the adjoining cover sections will be at different levels. It will also be noted that the reducing covers or rings at the same level may be used on any particular drop ring, so that vessels of whatever character can be placed at any predetermined distance from the place of combustion.

It will be seen that a heating apparatus constructed in accordance with my invention fulfills the objects enumerated besides possessing other advantages.

My invention in its broader aspects is not limited to the precise construction shown and described nor to any particular construction by which the same has been or may be carried into effect as many changes may be made in the detail thereof without departing from the main principles of the invention.

What I claim is:

1. A candy stove including in combination, a combustion chamber, a burner arranged in operative relation to said chamber, a casing arranged about said chamber and forming a flue passage having a heating area substantially co-extensive with the dimensions of the vertical wall of the combustion chamber, said combustion chamber having its side walls provided with a plurality of annularly disposed vents communicating with said flue passage, means including an upright, shiftable vent-provided device for regulating the passage of the heated prod-

ucts of combustion through said vents, and a top overlying said chamber and comprising a plurality of annular sections arranged one within the other and at different levels and having approximately vertical walls, each inner section being supported by the next outer section; the vents being formed in the combustion chamber in close proximity to said top whereby the heat-units from the flue passage may be directed against the vertical wall of each annular section of the top.

2. A candy stove including in combination, a combustion chamber, a burner arranged in operative relation to said chamber, a casing arranged about said chamber and forming a flue passage having a heating area substantially co-extensive with the dimensions of the vertical wall of the combustion chamber, said combustion chamber having its side walls arranged to form vents communicating with said flue passage, means for regulating the passage of the heated products of combustion through said vents, and a top comprising a series of sections arranged at different levels and having approximately vertical walls, each lower section being supported by the next upper section, and the lowermost section comprising a plurality of sections arranged at the same level, one within the other, and each inner section being supported by the next outer section; the vents being formed in the combustion chamber in close proximity to said top whereby the heat-units from the flue passage may be directed against the vertical wall of each annular section of the top.

3. A candy stove including in combination, a combustion chamber, a burner arranged in operative relation to said chamber, a casing arranged about said chamber and forming a flue passage having a heating area substantially co-extensive with the dimensions of the vertical wall of the combustion chamber, said combustion chamber having its side walls provided with a plurality of annularly-disposed vents communicating with said flue passage, means including an upright, shiftable vent-provided device for regulating the passage of the heated products of combustion through said vents, and a top overlying said chamber and comprising a series of annular sections or rings, each ring having a vertically inclined portion or wall, an upper horizontal flange portion adapted to engage a similar flange and be supported thereby, and a lower horizontal flange portion adapted to engage a similar flange; the vents being formed in the combustion chamber in close proximity to said

top whereby the heat-units from the flue passage may be directed against the vertical wall of each annular section of the top.

4. A candy stove including in combination, a combustion chamber, a lining for said chamber of non-heat-conducting material, a burner arranged in operative relation to said chamber, a casing arranged about said chamber and forming a flue passage having a heating area substantially co-extensive with the dimensions of the vertical wall of the combustion chamber, said combustion chamber having its side walls provided with a plurality of annularly-disposed vents communicating with said flue passage, means including an upright, shiftable vent-provided device for regulating the passage of the heated products of combustion through said vents, and a top overlying said chamber and comprising a plurality of annular sections arranged one within the other and at different levels and having approximately vertical walls, each inner section being supported by the next outer section; the vents being formed in the combustion chamber in close proximity to said top whereby the heat-units from the flue passage may be directed against the vertical wall of each annular section of the top.

5. A candy stove including in combination, a combustion chamber, a burner arranged in the bottom of said combustion chamber, oppositely flaring walls rising from the opposite sides of said burner to direct the flow of the heated gases from said burner, a casing arranged about said chamber and forming a flue passage having a heating area substantially co-extensive with the dimensions of the vertical wall of the combustion chamber, said combustion chamber having its side walls arranged to form vents communicating with said flue passage, means for regulating the passage of the heated products of combustion through said vents, and a top comprising a plurality of annular sections arranged one within the other and at different levels and having approximately vertical walls, each inner section being supported by the next outer section; the vents being formed in the combustion chamber in close proximity to said top whereby the heat-units from the flue passage may be directed against the vertical wall of each annular section of the top.

In testimony whereof, I have signed my name to this specification, in the presence of two subscribing witnesses.

HENRY W. O'DOWD.
